W. W. HAWKINS

IGNITION EQUIPMENT

Filed Feb. 20, 1922

UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

IGNITION EQUIPMENT.

Application filed February 20, 1922. Serial No. 537,981.

To all whom it may concern:

Be it known that I, WILLIAM W. HAWKINS, a citizen of the United States, and resident of Brooklyn, in the county of Kings and State of New York, have invented a certain new and useful Improvement in Ignition Equipments, of which the following is a full, clear, concise, and exact description, reference being had to the accompanying drawings, forming a part of this specification.

My invention relates to an ignition equipment comprising a low tension oscillating magneto and spark electrodes which are operated in timed relation to the magneto.

Among its objects, my invention contemplates the provision of:

First: An ignition equipment comprising novel means for maintaining the generating circuit of the magneto open during the cocking movement of the rotor thereof;

Second: An ignition equipment comprising improved means for maintaining the spark electrodes in tight engagement during the "recoil" movement of the rotor; and

Third: An oscillating magneto ignition equipment comprising novel means for separating the electrodes very quickly at the proper instant in the cycle of magneto operation.

These and other objects and advantages of the apparatus of my present invention will appear as the following detailed description progresses.

In the accompanying drawings illustrating my invention:

Figure 1 is a side elevational view of the magneto ignition equipment embodying my invention;

Figure 2 is an end view of the bracket, the magneto generating springs and certain connected parts being illustrated in dotted lines. That part of the magneto rotor shaft with which my invention is particularly concerned is illustrated in section in this figure, the plane of the section being indicated by the line 2-2 of Figure 1;

Figure 3 is an end view of the igniter plug, this view illustrating the movable electrode in its normal or open position; and

Figure 4 is a similar view illustrating the movable electrode in its closed position.

Similar characters of reference refer to similar parts throughout the several views.

The ignition equipment of my invention 55 preferably includes an integral plug and bracket structure comprising the igniter plug 10, magneto shelf 11 and the plate 12, which is provided with apertures 13-13 for the reception of bolts wherewith the plug and bracket structure is secured to an engine cylinder with the igniter plug extending into a suitable opening in the cylinder in the usual manner.

The igniter plug is provided with the stationary or insulated electrode 14 and with the grounded or rocking electrode 15. The electrodes are provided at their inner ends with the usual opposed igniter points 14^a and 15^a, as illustrated most clearly in Figures 3 and 4. At 16 is illustrated a coil spring which normally holds the annular beveled shoulder of the grounded electrode in gas tight contact with its co-operating correspondingly shaped seat in the inner end 75 of the igniter plug.

At 17 is illustrated a low tension magneto of any approved design, the magneto frame being securely bolted to the shelf 11, as illustrated. The magneto rotor shaft is illustrated at 18. That end of the rotor shaft which lies away from bracket portion 14 is provided with a yoke 19, and associated with this yoke are the customary generating springs 20-20, one end of each of these 85 springs being attached to the yoke, the other end of each spring being attached to one of the stationary spring posts 21-21. In the present embodiment of my invention, spring posts 21-21 are carried by a plate 22 which 90 is fixed with respect to the magneto field structure.

It will be understood that one end of the magneto generating winding is grounded to the magneto frame and thence to the bracket 95 and that the other side of the generating winding is connected by insulated lead 23 to a suitable terminal clip 24 which is in electrical contact with the insulated electrode 14.

In the operation of the magneto, the rotor shaft is periodically cocked against the tension of generating springs 20-20 and released, the rotor being then quickly returned to its normal position by springs 105 20-20. In Figures 1 and 2, the rotor shaft is illustrated as it appears prior to the commencement of its recoil movement. The en-

gine driven actuator which cocks the rotor shaft is indicated by dotted lines at 25 and the magneto "push finger" with which the actuator or push rod co-operates is indicated at 26. This "push finger" is, of course, fixed with respect to the magneto rotor shaft and is conveniently formed integral with or located adjacent to the yoke 19.

As thus far described, the ignition equipment of my present invention need not differ in any material respect from the "Webster oscillator" which is now well known to persons familiar with the art to which my invention relates.

15 I shall now proceed to describe those parts of the apparatus which are the salient features of my present invention.

Fixed to and extending downwardly from the outer end of the movable electrode 15 20 is an arm 26. At 27 is illustrated a curved leaf spring which has one leg thereof fixed to a bracket stud 28. The spring 27 extends upwardly over the adjacent end of the movable electrode and then downwardly, the 25 right-hand leg of the spring (Figure 2) being attached to the movable electrode arm 26 by a screw 29. The last mentioned leg of spring 27 extends somewhat below arm 26 for a purpose which will presently be 30 explained.

The legs of spring 27 tend to move apart; hence said spring at all times tends to hold the arm 26 in the position illustrated in Figure 2. When arm 26 is in the position 35 illustrated in Figure 2, the igniter points are separated, as indicated by dotted lines in said figure. At 30 I have illustrated a stop pin which is carried by bracket portion 12 and which prevents spring 27 from moving the arm 26 in a counter-clockwise direction beyond the position illustrated in Figure 2.

I now call attention to the collar 31 which is keyed upon that end of the rotor shaft which lies next adjacent the bracket portion 40 12. Collar 31 is provided with a bifurcated portion 32 in which a movable finger 33 is pivoted by means of a pin 34. A leaf spring 35, carried by collar 31, normally retains one end of finger 33 in engagement with 45 collar portion 32. The other end of finger 33 is provided with an inclined surface 36, the purpose of which will presently appear.

50 Normally the magneto yoke stands horizontally. At this time the pivoted finger 33 lies to the left (Figure 2) of the free end of U-shaped spring 27. The igniter points are normally held separated under the influence of spring 27.

60 Now let us assume that the engine driven actuator 25 engages the push finger 26 and moves the magneto rotor shaft against the tension of springs 20-20 to the "cocked" position illustrated in Figure 2. The igniter points remain open during the cocking

movement. This is very desirable, because, with the contacts open during the cocking movement, no current wave is built up in the generating winding of the magneto during the cocking movement thereof. Consequently, the current wave built up in the generating winding during the succeeding or "recoil" movement of the rotor is permitted to build up from datum instead of from a point below datum, as would be the case if the igniter contacts were closed during the cocking movement of the rotor. When, during the cocking movement of the rotor, the finger 33 engages the free end of spring 27, the light spring 35 yields to permit the inclined surface 36 of the finger to slip past the free end of spring 27, the finger assuming the position shown in Figure 2.

Now let us assume that the actuator 25 disengages the push finger 26 and that the rotor shaft and parts carried thereby recoil under the influence of springs 20-20. When this occurs the finger 33 engages the free end of spring 26 and moves said end of the spring to the left (Figure 2). Arm 26 is consequently turned clockwise (Figure 2) and the electrode points are closed and held forcibly closed until the peak of the current wave generated by the magneto is attained. 95 At the instant that the current wave generated by the magneto attains its peak, or approximate peak, the finger slips under the free end of spring 27. Spring 27 thereupon very suddenly opens the igniter points to 100 permit the passing of an ignition spark therebetween.

It will be understood that the construction and arrangement of parts herein shown and described insures that the igniter points will 105 be held firmly in contact during the recoil movement of the rotor and also insures that the igniter points will be very quickly separated at the proper instant in the cycle of magneto operation.

Having thus illustrated and described a preferred embodiment of my invention, I do not limit myself to the precise construction and arrangement of parts herein shown and described, but wish to avail myself of all 110 other embodiments of the invention defined by the appended claims.

What I claim as new and desire to secure by Letters Patent of the United States is:

1. An ignition equipment comprising an igniter plug, stationary and rocking electrodes carried by said plug, contacts carried by said electrodes, an arm carried by the outer end of the rocking electrode, a leaf spring having one end fixed with respect to the igniter plug and being attached near its other end to said arm, said spring normally holding the contacts separated, and means adapted to engage said leaf spring 120 to close the contacts against the action of 125

said leaf spring and then to disengage said spring to permit same to open the contacts.

2. An ignition equipment comprising an oscillating magneto, stationary and rocking electrodes, contacts carried by said electrodes, spring means normally holding said contacts separated, and means carried by the magneto rotor adapted forcibly to move the rocking electrodes and to close the contacts 10 against the action of said spring means during the recoil movement of the magneto rotor and to permit said spring means to separate the contacts near the end of the recoil movement of the rotor.
- 15 3. An ignition equipment comprising an oscillating magneto, spark electrodes, spring means normally holding said electrodes separated, and means carried by the magneto rotor adapted to close the contacts 20 against the action of said spring means during the major portion of the recoil movement of the rotor and to permit said electrodes to separate under the action of said spring means near the end of the recoil 25 movement of the rotor.

4. An ignition magneto equipment comprising an oscillating magneto, stationary and movable spark electrodes, spring means at all times tending to hold the movable electrode out of engagement with the stationary electrode, and means carried by the magneto rotor adapted to move the movable electrode against the action of said spring means, and maintain the electrodes 30 closed during the major portion of the recoil movement of the rotor, said spring means being adapted to separate the electrodes near the end of the recoil movement of the rotor.

40 5. An ignition equipment comprising an oscillating magneto, stationary and movable spark electrodes, spring means adapted to maintain the electrodes separated during the entire cocking movement of the magneto 45 rotor, and means carried by the magneto rotor adapted to close the electrodes during the major portion of the recoil movement of the rotor, said spring means adapted to separate the electrodes near the end of the recoil movement of the rotor.

50 6. An ignition equipment comprising an oscillating magneto, stationary and movable spark electrodes, a leaf spring which normally holds the electrodes separated, and means carried by the magneto rotor for closing the electrodes during the major portion of the recoil movement of the magneto

rotor and for permitting said spring to separate the electrodes near the end of the recoil movement of the rotor, said rotor carried means comprising a spring-pressed finger adapted to engage, move, and disengage said leaf spring during the recoil movement of the rotor, said finger adapted to slip past said leaf spring without substantially flexing the same during the cocking movement of the rotor.

60 7. An ignition equipment comprising an oscillating magneto, stationary and movable electrodes therefor, a spring associated with the movable electrodes and adapted to hold the electrodes separated during the cocking movement of the magneto rotor, means associated with the magneto adapted to hold the electrodes closed against the action of 70 said spring during the major portion of the recoil movement of the rotor, said spring being adapted to separate the electrodes near the end of the recoil movement of the rotor.

75 8. In combination, stationary and movable spark electrodes, an oscillating magneto for supplying current thereto, a spring connected with the movable electrode and normally holding the same out of engagement with the stationary electrode, said 80 spring adapted to hold the electrodes separated during the major portion of the cocking movement of the magneto rotor, means carried by the magneto rotor adapted to close the electrodes against the action of said 85 spring during the recoil movement of the rotor, said spring being adapted to separate the electrodes near the end of the recoil movement of the rotor.

90 9. In combination with stationary and movable spark electrodes and an oscillating magneto for supplying current thereto, a spring at all times tending to hold the electrodes separated and trip mechanism interposed between the movable electrodes and the magneto rotor whereby the electrodes remain open during the cocking movement of the rotor, are held closed during the major portion of the recoil movement of the rotor, and are separated by said spring near 95 the end of the recoil movement of the rotor, seriatim.

In witness whereof, I hereunto subscribe my name this 27th day of January, 1922.

WILLIAM W. HAWKINS.
